UNITED STATES PATENT OFFICE.

CORYDON WHEAT AND ALFRED CATCHPOLE, OF GENEVA, NEW YORK.

HEATING APPARATUS.

SPECIFICATION forming part of Letters Patent No. 268,580, dated December 5, 1882.

Application filed March 15, 1882. (No model.)

To all whom it may concern:

Be it known that we, CORYDON WHEAT and ALFRED CATCHPOLE, both of Geneva, Ontario county, New York, have invented a certain new and useful Improvement in Heating-Apparatus; and we do hereby declare that the following is a full, clear, and exact description of the same, reference being had to the accompanying drawings, in which—

Figure 1 is a central vertical section of a boiler, showing our improvement. Fig. 2 is a similar view at right angles to Fig. 1. Fig. 3 is a section of one side of the upper portion of the apparatus, showing more particularly the means for extending the height of the magazine. Fig. 4 is a plan view of the lower sectional ring, C. Fig. 5 is a plan of one of the upper sectional rings D. Fig. 6 is a horizontal section of one of the upper rings D, enlarged. Figs. 7 and 8 are cross-sections of one of the rings D respectively in lines x x and y y of Figs. 5 and 6. Figs. 9 and 10 are detail views, showing the registers and slides. Fig. 11 is a bottom view of the dome. Fig. 12 is an elevation 25 of two of the rings D, exhibiting the notches therein for admitting the tubular door.

This improvement relates to steam-heating apparatus.

The objects sought in the invention are simplicity and cheapness of construction, safety against over-pressure, due to the form of the sectional rings, convenience of transportation, and ability to build up boilers of varying sizes with great facility and ease, either in stationary or portable form.

The invention consists in the construction and arrangement of parts hereinafter more definitely described and claimed.

In the drawings, A shows a base, forming the support for the sectional tubular rings, and having a grate, B, of ordinary form.

C is a hollow tubular ring, which rests upon this base, the passage through the ring being unobstructed, and said ring having two or more open-topped bulbs or enlargements, a a, Fig. 4, which allow the water to pass into the upper rings, which are of larger diameter.

D are the upper sectional tubular rings, of which any desired number may be used, according to the size of boiler it is necessary to make. These rings are simply laid one on top of another, with suitable attaching devices for

holding them firmly together. Each of the rings D is constructed as follows: It is made hollow for the free passage of water. It may be made of any desired form, both in outline and cross-section; preferably, however, the rings are square in cross-section, to facilitate casting and to fit better in building up. On opposite sides are ports or passages b b, Fig. 5, which fit over the bulbs a a of the lower ring, C, and which fit over each other in the successive sections, so as to make a connected passage on the two opposite sides clear up to the top of the boiler. The ring is also provided with a series of open-ended flue-tubes c c, arranged around the whole circumference, and when the rings are built up one on top of another these flue-tubes all come in line and make connected passage-ways from bottom to top, as shown in Fig. 2. At the bottom they open outside the lower base-ring, C, which is of smaller diameter than the other rings, and at the top they open into a space, d, communicating with the fire-chamber E.

F is a hollow dome-section, which fits on top of the upper ring D, and has ports corresponding with the ports b b, by which the hot water is allowed to enter the dome. It has also a downwardly-projecting flange, e, which rests on top of the upper ring, thereby forming the fire-space d, before described. It has likewise tubular passages f f, covered by stoppers g g, through which a poker, brush, or rod may be inserted into the flues c c, for the purpose of cleaning the latter from soot and ashes. The parts thus constructed are all bolted together by bolts or rods h h, which extend down from the dome through the ports b b, and are secured in place by nuts. The ports b b are divided centrally and vertically by partitions or webs i i, which extend to and join with the adjacent ends of the two flues c c next to them, but extend no farther, so that the flues c c beyond are disconnected from each other and the water can flow freely around and between them. The partitions all coincide, and their ends meet, making thereby passage-ways from top to bottom. The dome F has the same partitions i i; but they are cleft or slotted in the center, as shown in the bottom view, Fig. 11. By the means of these partitions i i a double passage-way is made from top to bottom, and the hot water will ascend the inner passage while the

cool water will descend the outer passage, thus making a circuit, as indicated by the arrows, Fig. 7. In addition to this the partitions *i i* form posts or piers to strengthen the rings and prevent any crushing or springing of the rings under pressure.

G is an open-ended ring or cylinder, which rests on top of the dome, and which we denominate the "smoke-stack," since it has a smoke-pipe, *H'*, extending from its back and opening into the main smoke-pipe *H*. On top of this ring rests the flange *j* of a cylinder, *I*, of smaller diameter, which rests within and extends through the ring, and has attached at its lower end the magazine *J*. The cylinder *I* has in its sides and near the top a series of small holes, *s² s²*, which open outward into the space between the cylinder and the ring *G*, and form passages for the escape of gas from the top of the magazine into said space, whence it escapes through pipe *H'* into the main smoke-pipe *H*. By this means a free escape of gas is allowed and all danger of explosion is obviated.

The magazine is made of a series of overlapping rings, *k k*, forming sections that can be applied or removed at any time to make the magazine longer or shorter to correspond to the height to which the boiler is built up. The cylinder *I* rests between projecting lugs *l l* in the eye of the dome, which center the cylinder and leave a circular space, *m*, through which the smoke and products of combustion can pass from the fire-chamber to the exit-pipe *H'* in the ring *G*. On the flange *j* of the cylinder *I* is a groove, *n*, in which fits the edge of the cover *L*, as shown in Fig. 2; or, in case it is desired to build the magazine higher, one or more rings, *M*, may be placed on the top of the cylinder *I*, and the cover be placed on top of the upper ring, as shown in Fig. 1. The grooves in which the edges rest are filled with sand to form a packing, and prevent the escape of gas. By this construction it will be seen that the magazine and its connections are portable and can be removed and replaced without difficulty, and, furthermore, the magazine is supported and retained in place by the ring *G*, and not by the boiler. In this manner the capacity of the magazine may be increased at pleasure.

N is a jacket or casing, surrounding the sectional rings and connecting the base with the dome, and leaving a thin space between itself and the rings, which simply forms a flue for the escape of the products of combustion.

o o, Fig. 5, are flanges forming partitions, which stand radially and vertically up and down between this jacket and the rings *D D*, and divide the annular flue-space into as many different and separate flues *p p* as there

o o are flanges. These flanges come on a line between the flues *c c* of the rings *D D*, so that the flue-spaces *p p* each comes opposite and covers one of the flues *c c*, thereby imparting the maximum of heat to the water, which lies in a thin body between the two flues. These flanges *o o* keep the heat from circling around indefinitely, and confine the heat to straight

currents covering the flues *c c*. The flanges *o* extend from the bottom of the lower ring *D* to the top of the upper one, their length therefore being exactly the vertical height of the rings *D D*, and leaving the spaces above and below the rings open and unobstructed.

P is an exterior casing or jacket, extending from the base to a little distance above the dome, where it is carried in and strikes the ring *G*, thereby forming a jacket-space around the inner casing, *N*. Cold air is let in at the bottom of the exterior jacket-space and is passed out at the top through a pipe or pipes, and may be used to heat outside rooms. The exterior jacket serves to prevent the passage of heat outward, thus serving as a shield. If desired, it may be dispensed with entirely. Slides or covers *r r* are made in both the outside and inside casings to allow entrance to the space around the rings for the purpose of clearing the same of ashes and soot, which are swept out through holes provided with stoppers *s s*, as shown in Fig. 1.

H² is a branch of the smoke-pipe, which passes in and connects with the inner flue-space between the inner jacket and the rings. Both of the smoke-pipe branches *H' H²* have dampers *u u*, by which the draft can be controlled.

v is a sliding register on the flange *e* of the dome *F*, covering openings through said flange. By moving the register in one direction the draft from the fire-chamber will pass through the openings, and by moving it in the other direction the draft will be cut off. This is of service sometimes where it is desired to produce a draft less intense than that through pipe *H'* and more intense than that through pipe *H²*. The register *v* is on the opposite side from the smoke-pipes, and the draft therefrom has to make a half-circuit before it reaches the smoke-pipe *H²*, where it escapes.

R is a circular tubular door, set into the boiler through the casings and the rings, and reaching to the fire-chamber *E*, as shown in Fig. 2, by which means the fire may be reached at any time. The outer end is covered by a door or flap, *w*. To allow the inner end of the tube to pass through the rings *D D*, two of said rings have openings or notches *t t* made therein, as shown in Fig. 12, the notch in each extending one-half the width of the ring, but leaving a free passage-way for the water above the notch, so that the water can circulate throughout the whole ring, thereby preserving uniformity in the expansion of the ring under heat. The tube *R* enters the opening thus made and makes a clear passage from the outside of the boiler to the fire.

S is the piping which leads off from the top of the boiler through the building to be heated, and *T* is the return-pipe, arranged in the ordinary way.

From the above description the operation will be readily understood. The water as it becomes heated in the rings rises through the inner passages to the top and then descends

through the outer passages, thus making a constant circulation. It also spreads and circulates throughout each ring, and in coming in contact with the flues *c c* it receives additional heat. In kindling or starting the fire, the valve *u* in smoke-pipe *H'* is opened, which allows a direct draft upward, the draft passing through the circular space *m*. When the fire is properly established this valve is closed and the valve in pipe *H²* is opened. The draft then passes up through the fire-chamber over the top of the rings; thence passes down through the flues *c c*, and thence passes up again through the flues *p p*, between the jacket *N* and the rings, and finally escapes, the heat thus surrounding both the inner and outer sides of the rings also passing through the center, obtaining the best effect of the heat. By making the lower ring, *C*, of smaller diameter than the others, a space is left around the bottom which allows the draft to turn and circulate, and also gives room to clear out ashes and soot. The damper *v* allows an intermediate draft between the direct and indirect when desired.

25 The dome *F* is of peculiar construction. It is hollow and receives steam and water through ports communicating with the rings below. It has a central eye or opening, through which the ring passes which supports the magazine. 30 It has a vertical flange or skirting, which rests upon the upper ring and forms a fire space at the top of the fire-chamber, and it has an inclined bottom, which allows water to stand thereon when the dome is dry, thereby obviating cracking of the same under heat.

35 Having thus described our invention, we claim—

1. In a heating apparatus consisting of a series of hollow water-sections placed one upon another, the bottom section, *C*, of less diameter than the upper sections, *D*, and communicating therewith by ports *a a*, the upper sections offsetting or projecting beyond the bottom section, leaving a space in the bottom of the boiler, into which the flues *c c* of the upper sections open, and in which are located the stoppers *s s*, as herein shown and described.

2. In a heating apparatus, the hollow ring or section *D*, constructed with the ports or 45 openings *b b* on opposite sides, forming waterways, the vertical partitions *i i*, dividing said ports, and the flues *c c*, extending vertically

through the ring, all in combination, as shown and described, and for the purpose specified.

3. In a heating apparatus, the combination 55 of the several water rings or sections *D D*, placed one on top of another, forming a stack, said rings provided on opposite sides with ports *b b*, divided vertically by partitions *i i*, forming distinct water-channels from bottom 60 to top of the rings, and provided with flues *c c*, forming draft-passages through the rings, as and for the purpose specified.

4. In a heating apparatus, the combination 65 of the dome *F*, having a central eye or opening, the separate ring *G*, resting on top of the dome, surrounding the eye or opening, and provided with an exit-pipe, *H'*, which communicates with the main exit-pipe, and a loose cylinder, *I*, resting on top of the ring *G*, extending down through the dome, forming an attachment for the magazine, and having in its sides near the top a series of small holes, *s² s²*, for the escape of gas from the magazine into the space between the cylinder and ring, and 70 thence to the exit-pipe, as herein shown and described.

5. In a steam-heating apparatus consisting of a series of water-sections placed one upon another, the hollow dome *F*, constructed with 80 the vertical flange or skirting *e*, which elevates it above the water-section below, the series of tubes *f f*, which coincide with the flues *c c*, in the water-sections, and with a bottom plate which inclines slightly downward from the 85 outer to the inner periphery, as shown and described, and for the purpose specified.

6. In a steam-heating boiler, the combination, with the sectional rings *D D* and the casing *N*, of the radial flanges or partitions *o o*, 90 resting between the rings and the casing, said flanges extending from bottom to top of the series of rings, and forming flues *p p*, which come opposite the flues *c c* of the rings, as herein shown and described.

95 In witness whereof we have hereunto signed our names in the presence of two subscribing witnesses.

CORYDON WHEAT.
ALFRED CATCHPOLE.
